DESIGN FOR A COOKING-RANGE.

Design No. 12,695, dated January 17, 1882.

UNITED STATES PATENT OFFICE.

OLIVER B. KEELEY, OF SPRING CITY, PENNSYLVANIA.

DESIGN FOR A COOKING-RANGE.

SPECIFICATION forming part of Design No. 12,695, dated January 17, 1882.

Application filed December 19, 1881. Term of patent 7 years.

To all whom it may concern:

Be it known that I, OLIVER B. KEELEY, a citizen of the United States, and a resident of Spring City, Chester county, Pennsylvania, have invented a Design for a Cooking-Range, of which the following is a specification.

My design for a cooking-range is fully shown in the accompanying drawing.

The main oven-door A has a flat border, *a*, 10 with line-engraving, and a central raised panel, *b*, with diagonal title, letter and line-engraving. The water-reservoir has a curved lower end and a panel, *d*, with raised and engraved center, and lower edge curved to accord with 15 that of the reservoir. The fire-place door B has a flat border, *e*, and raised center with three mica panels, *f*. The ash-pit door D has a flat border with raised and engraved center. The base of the stove has a projecting ledge, 20 *E*, with line-engraving, and a skirting, *F*, also engraved. The feet *G* are three-faced, and the top of each foot has on each of its faces a raised pyramidal boss, *g*.

I claim—

25 1. The design for the main door A, said design comprising the flat border *a* and raised

center with diagonal title, letter and line-engraving, as shown and described.

2. The design for the water-reservoir, said design comprising the curved lower end and 30 panel with raised center and curved lower edge, as shown and described.

3. The design for the door B, said design comprising the flat border *e* and raised center with panels *f*, as shown and described. 35

4. The design for the base, said design comprising the projecting ledge *E* and skirting *F*, engraved as shown and described.

5. The design for the feet *G*, said design comprising the three faces, each with a raised 40 pyramidal boss, *g*, as shown and described.

6. The design comprising the doors A B D, reservoir with panel *d*, base with ledge *E*, and skirting *F* and feet *G*, as shown and described.

In testimony whereof I have signed my name 45 to this specification in the presence of two subscribing witnesses.

OLIVER B. KEELEY.

Witnesses:
